POWER LINE FOR ANTENNAE

Felix Gerth, Berlin-Tempelhof, Germany, assignor to C. Lorenz Aktiengesellschaft, Berlin-Tempelhof, Germany

Application December 20, 1932, Serial No. 648,079
In Germany May 31, 1932

3 Claims. (Cl. 250—33)

In the high frequency art, as is well known, at the various stations so-called power or transmission lines are employed, which usually consist of two parallel conductors. These are traversed 5 in phase opposition by the high frequency to be transmitted, so that the external fields are cancelled and therefore there is no radiation. It may, however, happen that the conductors are also traversed by co-phasal currents in addition 10 to the currents in phase opposition. This is the case, for example, with lines which serve to feed antenna systems. In this case the line is situated in the field of the radiating antennæ. The closely adjacent conductors of these power lines are induced 15 by this field in the same direction, so that on account of such radiation-coupling co-phasal currents flow. These currents cause the power line to radiate and thereby the directional characteristic of the antenna arrangement may be undesirably influenced. It is the object of the present 20 invention to control these co-phasal currents. According to the invention these co-phasal currents are prevented from flowing or are neutralized, or their current loop is so located that the 25 radiation characteristic of the antenna arrangement is improved or a desired radiation diagram is obtained.

Several embodiments of the invention are shown in the accompanying drawing. Figure 1 is a 30 schematic elevation of one of such embodiments, Figure 2 the ground plan of a second embodiment. Figure 3 is a diagram of a third embodiment. Figure 4 is a schematic elevation of a fourth embodiment.

In the arrangement shown in Figure 1, an antenna A of any antenna arrangement is fed 35 from the transmitter S over the power line E. In the middle of the line E is inserted a coil arrangement L that consists of two interwound coils, 40 which are wound in the same direction and are closely coupled together. One of these coils is inserted in each of the two conductors of the line E. The inductances of these coils neutralize one another for the counter-phasal currents coming 45 from the transmitter so that in this desired direction the power can flow unhindered. With the 50 co-phasal currents induced by the radiation of the antenna A, however, the inductances are added, so that the currents find a resistance which does not permit them to flow.

The coils L may be repeated in the line E at certain intervals, which are preferably equal.

Figure 2 shows a horizontal flat antenna structure comprising a central emitter Z and outer 55 emitters A, which surround the emitter Z and

are supplied with power from the centre of this structure. The centre is connected through a power line B with the transmitter S. Power lines H also extend from the transmitter S to each of the power lines E for the sake of simplicity, only 60 one of such lines H is shown. This is so coupled with its line E at G and with the transmitter S that the current transmitted by the line H is of correct phase and amplitude for the suppression 65 of the co-phasal currents in the line E. According to the circumstances the co-phasal energy in both conductors of the energy line E may thereby be suppressed, or within certain limits an asymmetry may be allowed by suppressing the co-phasal currents only in that conductor of the power line E in which the co-phasal current is opposed to the co-phasal current from the transmitter S. 70

In the embodiment shown in Figure 3 a certain combination of the lines E, H is shown. Power is 75 conveyed from the line E over a coupling arrangement K, to a device V where a phase displacement is effected. In the output circuit of the phase-changing device V, is the coupling arrangement G, by which the compensation is effected in the 80 same manner as in the arrangement according to Figure 2. The energy for compensating is thus obtained from the line E itself.

In the device according to Figure 4 the antenna A consists of dipoles D, whose centres of 85 radiation are situated at $\lambda/4$ height above the ground. λ represents the wave-length. In the line over which the transmitter S feeds the dipoles, tuning means A' are inserted, which are so arranged that the current loop of the co-phasal 90 currents is situated as near as possible to the dipoles. Thereby the co-phasal currents produce a field in the line E outwards, which is approximately identical with the field generated by the dipoles D. In this manner the radiation fields of 95 the dipoles and of the line E may be made more or less to coincide and consequently the radiation characteristic of the antenna arrangement is improved and undesired field distortions are substantially avoided. 100

The current loop of the co-phasal currents need not necessarily coincide with the radiation centres, but may, for example, be placed in the vicinity of the earth's surface. In this manner by a suitable choice of the phase, that is by a 105 certain construction of the line E or by the insertion of phase shifting means, amplification of the radiation diagram is obtained in a similar manner as though a short vertical conductor were situated on the ground, and tuned in conjunction 110

with earth. Thus any desired intensification of the radiation diagram may be obtained.

What is claimed is:

1. In a power line for antennæ that consists of 5 conductors parallel to each other, the combination with an antenna structure of means for causing counter-phasal currents to flow in these conductors, and means for locating the current loop of the co-phasal currents in the vicinity of 10 the radiation centre of said antenna structure and for causing the direction of the co-phasal currents adjacent the antenna structure to be such as to augment the radiation field thereof.
2. In a power line for antennæ which consists of 15 conductors parallel to one another, the combination with an antenna structure of means for causing counter-phasal currents to flow in these

conductors, and means for locating the current loop of the co-phasal currents at a point which is distant from the radiation centre of the said antenna structure.

3. In combination, an antenna structure, a transmission line in the radiation field of said antenna structure and comprising parallel conductors, means for supplying high frequency currents over said transmission line to said antenna structure, and means for so locating the loop of and phasing the co-phasal currents induced in the conductors of said transmission line with respect to the current in the antenna structure as to improve the radiation characteristic of the antenna structure. 80 85 90
